Clarke & Chapman Atty.

UNITED STATES PATENT OFFICE.

THOMAS H. COSTELLO, OF CHICAGO, ILLINOIS; ROSE M. COSTELLO AND WILLIAM E. COSTELLO, EXECUTORS OF SAID THOMAS H. COSTELLO, DECEASED, ASSIGNORS TO ROSE M. COSTELLO, TRUSTEE.

MAP RACK.

Application filed October 3, 1924. Serial No. 741,399.

My invention relates to frames or cases for holding maps, charts and the like for display and reference or when not in use. Among the objects thereof are the provision 5 of a knock-down frame or case of novel construction which, when unassembled, is compact for storage and shipment, and which may be readily assembled or disassembled whenever necessary or convenient.

10 My invention further provides a novel device by which spring rollers on which the maps are mounted are secured in the frame against displacement, and from which the operative spring shafts may be readily detached while leaving the spring under tension. My invention is simple in construction and the amount of labor and expense required to prepare and assemble the several parts is reduced to a minimum.

15 The principles of my invention are illustrated in the drawings in which Fig. 1 is a front elevation; Fig. 2 is a cross-section of Fig. 1 on the line 2—2 thereof; Fig. 3 is a vertical section on line 3—3 of Fig. 1; 20 and Fig. 4 is a partial section of Fig. 1 on the line 4—4.

Further describing my invention with reference to the drawings in which like characters of reference denote like parts throughout: Numerals 1 and 2 are respectively the 25 heading and base piece of a map holding frame; 3 and 8 are the connecting ends thereof. One of said connecting end pieces, designated by numeral 3, preferably consists of a unitary piece of wood having the 30 normal face 4 in which is cut from end to end the rebate 5 and the longitudinal groove 6. It also has in the said face the spaced holes 7 which are adapted to receive the 35 round, relatively stationary stub-shafts which are attached to one end of spring shade or map rollers. The other of said connected end pieces, designated by numeral 8, is preferably formed of a single piece of material 40 having the normal face 9 and has at the front inward corner a rebate 10 and further back on the inner face, in stepped relation with rebate 10, is a second and shallow rebate 11. A groove 12 extends 45 from end to end of said connecting end pieces 8 in the face of the said last named rebate.

A metal strip 15 to hold the flattened ends of the relatively revolute spring actuated

55 shafts at the outer end of said rollers is attached by screws 16 to the normal face 9 of end piece 8. The front edge of the said metal strip projects over rebate 11.

It will be seen that the end pieces are 60 adapted to the objects described and that they are also adapted to be formed as mouldings in a moulding machine or sticker so as to be carried in stock and put together as desired.

In the metal strip are formed a plurality 65 of recesses or pockets, each consisting of the narrow slots 18 and 19 angularly connected with each other and having a lug 20 forming a narrowed throat 21 through which the flattened ends of the spring-controlled shafts 70 may pass and be seated against rotation in the narrowed slot 19.

Positioning pieces 25 project from the bottom and top of the end pieces 3 and 8, and are received in corresponding holes 26 in the heading and base pieces 1 and 2. Numeral 27 indicates a plurality of rods or bolts at 75 each end of the frame, the body portions of which are adapted to be seated laterally within the bottoms of grooves 6 and 12 and to pass through corresponding holes in the base and heading pieces of the case. Said rods have heads 28 and are screw-threaded at 29 to take the nuts 30. Owing to the 80 breadth and thickness and unitary character of the end pieces 3 and 8, the end and horizontal pieces of the frame, when drawn together, form substantial bracing means for the frame-work as a whole. Hangers 31 formed from strips of narrow metal have 85 quarter turns at 32 and are provided with suspension holes 33 at the free end. Openings are provided in the other ends for pivot pins or screws 34 by which the hangers are 90 attached to the outer faces of the end pieces 95 so that, when turned upwardly and backwardly, one edge will contact with the under side of the projecting ends of the head pieces and be held in said relation to receive angle hooks or similar suspending devices in the suspension holes 33. As the 100 hangers are in rigid relation to the case or frame and the lower edges of the bottom piece are in contact with the wall on which the frame is hung, the frame will be given an inclination which is convenient for the operation of the maps as drawn out by the user or retracted by the spring rollers.

When it is desired to introduce maps in the frame, the round and relatively stationary stub-shafts will be received in the openings 7 in end piece 3 which form bearings therefor. The flattened spring actuated ends 22 are transversely introduced into the body portion 18 of slot 17 and given an approximately quarter revolution by which they are passed through the narrow neck 21 and seated in the pocket 19 wherein they are held by retaining lugs 20. By reverse movement, the flattened roller ends are turned free so as to pass lug 20 and are readily removed from the slots 17 and the rollers removed from the frame. The maps, as shown in the drawings, have map sticks 38 extending along the free edges and the outer ends should project at 39 and 40 to engage the bottom faces of the rebates 5 and 10 respectively which thus form stops against the maps being spun on the rollers when rolled up under tension of the springs.

It will be evident that the apparatus may be used as described and also equally evident that a back and suitable door may be attached if desired.

I claim:

1. In a map rack; a heading piece, a base piece, connecting end pieces having inwardly facing grooves throughout their length, positioning pieces attached to the end pieces and engageable with the heading and base pieces and bolts or rods to connect the top and base pieces adapted to be seated laterally within and be concealed by said inwardly facing grooves.

2. In a map rack; the combination of a heading piece, a base piece, connecting end pieces, said end pieces each being integrally formed and having inwardly facing grooves throughout their length, positioning pieces

attached to the end pieces and engageable with the heading and base pieces and bolts or rods to connect the top and base pieces adapted to be seated laterally within and be concealed by said inwardly facing grooves.

3. In a map rack having heading and base pieces, a connecting end piece having a front rebate and a second rebate stepped therefrom, and a metal strip provided with spaced pockets for spring provided shafts secured to the normal face of said end piece and projecting over the second rebate.

4. In a map rack having heading and base pieces, a connecting end piece having a front rebate and a normal face provided with spaced stub shaft holes, a second connecting end piece having a front rebate and a second rebate stepped therefrom, and a metal strip provided with spaced pockets for spring provided shafts secured to the normal face of said end piece and projecting over said second rebate.

5. In a map rack adapted to receive spring actuated rollers having flat ended stub shafts; a metal strip adapted to be mounted in said rack and provided with a plurality of slots or pockets, each slot comprising a substantially horizontally extended lateral portion and a connecting downwardly and forwardly extended retaining portion, said retaining portions being narrowed to receive the flattened end of a stub shaft and hold it against revolution, and being further provided with a retaining lug to hold the stub shaft against displacement.

In witness whereof, I have hereunto set my hand at Chicago, Illinois, this 1st day of October, 1924.

THOMAS H. COSTELLO.
